UNITED STATES PATENT OFFICE.

JAMES A. CLEMENTS, OF ABINGDON, ILLINOIS.

FARM-GATE.

SPECIFICATION forming part of Letters Patent No. 761,580, dated May 31, 1904.

Application filed February 24, 1904. Serial No. 195,072. (No model.)

To all whom it may concern:

Be it known that I, JAMES A. CLEMENTS, a citizen of the United States, residing at Abingdon, in the county of Knox and State of Illinois, have invented certain new and useful Improvements in Farm-Gates; and I do hereby declare that the following is a full, clear, and exact description of the same, reference being had to the annexed drawings, making a part 10 of this specification, and to the letters of reference marked thereon.

The present invention has relation to that class of farm-gates provided with operating-levers connecting with the latch thereof through suitable mechanism and ropes or pulls depending from the levers, whereby the same may be operated by equestrians or persons in vehicles; and the invention has for its object to provide a simple and practical swinging gate, with means connecting therewith for the opening and closing thereof without the necessity of dismounting from a horse or vehicle, said operating mechanism being both simple and perfect in its action, as well as 20 strong and durable.

The invention consists in a farm-gate constructed substantially as shown in the drawings and hereinafter described and claimed.

Figure 1 of the drawings is a perspective 30 view of a swinging farm-gate embodying my invention; Fig. 2, a horizontal section through the gate-post, showing a portion of the gate and operating mechanism connecting therewith on an enlarged scale; Fig. 3, an elevation of a portion of the gate-post and means for suspending the gate thereto; Fig. 4, an enlarged view, partly in section, of the latch mechanism, showing a portion of the outer gate-post and gate; Fig. 5, a detail perspective view of the lower end of the latch to which the spring is connected.

In the accompanying drawings, A represents the upright post, to which the gate B is suitably connected, and C the outer gate-post, 45 with which the latch of the gate engages to lock it in a closed position, as shown in Fig. 1 of the drawings.

The gate B may be of any suitable form and construction, and suitable strap-hinges a are 50 connected to the inner end of the gate, by

which the gate is suspended from the gate-post A, by means of the rod b, which rod engages the hinges and the eye-brackets c, secured to the post.

The gate may be of any suitable construction and suspended from the post in any preferred manner as found best adapted to the purpose.

A suitable lever D connects with the post A, and a similar lever E connects with the post F, said lever having depending handle bars or pulls d e, respectively, for operating the levers by the person in the vehicle, said levers and the handle bars or pulls being of any preferred construction. The lever D pivotally 65 connects with an upwardly-extending arm G, which is preferably secured to the post A at an acute angle to a horizontal, and said lever is pivotally connected to an upright clip h upon the controlling-lever H.

A guide-bracket I, preferably of wire, is secured to the upper end of the post A, and upon the side of the lever is suitably connected a strap-guide f, through which the guide-bracket extends, as shown in Fig. 2 of 70 the drawings.

The guide-bracket I, as well as the guide-strap f, may be of any preferred construction, and any suitable guides on the post and controlling-lever, respectively, which are 80 adapted to engage with each other and which will provide means for guiding the controlling-lever in its movement, may be substituted for the construction shown, such means also guiding the several levers in their proper 85 working position.

The guide-bracket I may be connected by nuts engaging the screw-threaded ends of the arms of the bracket, as shown, or by any other means that will admit of the bracket 90 being adjustable upon the post, so that its position thereon may be set outwardly or inwardly in order to set the guide-bracket to throw the downwardly-extending handle bars or pulls d e over the driveway to the point 95 desired. Upon the free end of the controlling-lever H is a bracket i, to which is connected the pitman-rod J and also connected to the end of the horizontal controlling-arm K, which arm is pivoted to a bracket j, se- 100

cured to the gate, the extremity or end of the horizontal controlling-bar engaging a guide-bracket *k*, which is also secured to the gate. The end of the horizontal controlling-bar *K* 5 has pivotally and adjustably connected thereto a suitable link *L*; said link at its lower end being pivotally connected to a bell-crank lever *M*, pivoted to the gate. To this bell-crank lever *M* is connected one end of a rod 10 *N*, which engages guide-loops *l* upon the gate, the opposite end of the rod engaging the gate-latch *O*. (Shown in detail in Fig. 4 of the drawings.)

The latch *O* is pivoted to the gate at *m* in 15 any preferred manner found most practical, said latch at its lower or pivotal end having a mortised seat *n* for a coiled spring *P*, the free ends of the spring bearing against the shoulder *o* upon the side of the latch and the 20 opposite end of the spring bearing against that portion of the upright shown at *p*.

The latch *O* has a hook *q* to enable the end of the wire rod *N* to engage therewith through the medium of a loop *w*, or any other means 25 may be provided that will form a loose connection between the latch and rod, and I do not wish to be understood as limiting my invention to any particular construction of latch or the spring connecting therewith, as 30 any suitable spring-actuated latch of whatever construction may be substituted for the latch shown that will successfully operate to lock the gate closed or release it when desired.

The gate-latch *O* in the present instance has 35 an elbow *s* for engaging a keeper *t* in the gate-post *C* to hold the gate in a closed position. A stop-pin *u* upon the latch is adjustable by being engaged with one of a plurality of holes *v*, the adjusted position of the pin limiting the 40 extent of movement of the latch as circumstances would require.

It should be noticed that the latch is entirely independent of the operating-levers when in its normal position and can be used 45 as a hand-latch, by means of the depending handle *Q* thereon, to enable it to be operated by the hand, as in case an equestrian wishes to pass through.

The upwardly-extending hook *q*, with which 50 the loop *w* engages, may be changed in form and construction so long as the connections will admit of the latch being operated by hand independent of the several levers when found desirable.

55 The lever *E* and the controlling-lever *H* are in reality one common lever, and I have shown it in the drawings as two separate levers spliced together; but this is not essential, as the lever may be constructed in one 60 separate piece of material and of sufficient length to extend beyond the post, to which may be connected the handle bar or pull.

The adjustability of the guide-bracket may 65 be obtained in any suitable and well-known manner, and one means shown to render the

bracket adjustable to or from the post *A* resides in the nuts *a'*, engaging the screw-threaded ends of the arms *b'* of the bracket, as shown in Figs. 1 and 2 of the drawings.

The gate may be adjusted vertically on the 70 rod *b* and held in its adjusted position by a set-screw *c'*, which passes through the eye of the upper one of the hinges *a*, or other means may be provided for this purpose.

Pulling down upon either one of the handle bars or pulls *d e* will cause the inner end of the lever *D* or the controlling-lever *H*, as the case may be, to be raised, and with this movement of the lever the outer end of the controlling-arm *K* will be raised, and said arm being pivotally connected to the gate and also engaging with the guide *k*, so as to play up and down therein, the pivoted link *L* and the pivoted bell-crank lever *M* and rod *N*, which connects with the latch *O*, will cause 85 said latch to disengage itself with the gate-post *C* and the gate to swing open, and when the gate is half-way open the handle bar or pull may be released, after which the gate will automatically finish its circuit in either direction, as the case may be.

In describing the several details of construction of the gate and operating mechanism therefor I wish it distinctly understood that the invention is subject to many modifications or changes as circumstances would require and which may be resorted to without in any manner departing from the principle of the invention.

Having now fully described my invention, 100 what I claim as new, and desire to secure by Letters Patent, is—

1. A swinging farm-gate and means for operating the same, comprising suitable upright posts, a horizontal controlling-lever pivotally connected to one of said posts and connecting with the opposite posts through the medium of suitable guides, an operating-lever pivotally connecting with the controlling-lever, a horizontal controlling-arm pivotally connected to the gate and suitably connected to the controlling-lever, a pivoted and adjustable link connecting with the horizontal controlling-arm, a pivoted bell-crank lever pivoted to the gate and to the end of the link, a spring-actuated latch, and a rod connecting the latch with the bell-crank lever, substantially as and for the purpose set forth.

2. A swinging farm-gate and means for operating the same, comprising suitable upright posts, a controlling-lever pivotally connected to one of said posts and connecting with the opposite post through the medium of suitable guides, an operating-lever pivotally connected to an arm extending from one of the posts, a horizontal controlling-arm pivotally connected to the gate, a pitman-rod connecting said arm with the controlling-lever, a link adjustably and pivotally connecting with the horizontal controlling-arm, a bell-crank lever 130

pivotedly connected to the gate and to the adjustable link, a spring-actuated latch having a hook and depending handle at its end, and a rod connecting the bell-crank lever with the latch through a loose connection whereby the latch may be made independent of the operating-levers through the medium of a loose connection to enable said latch to be operated

by hand, substantially as and for the purpose described.

In testimony whereof I affix my signature in presence of two witnesses.

JAMES A. CLEMENTS.
